Stephen Elliott

United States Patent Office.

STEPHEN ELLIOTT, OF RICHMOND, INDIANA.

Letters Patent No. 91,528, dated June 22, 1869.

IMPROVEMENT IN DOOR-SPRINGS.

The Schedule referred to in these Letters Patent and making part of the same.

To all whom it may concern:

Be it known that I, STEPHEN ELLIOTT, of the city of Richmond, county of Wayne, and State of Indiana, have invented new and useful Improvements in Door-Springs; and I do hereby declare that the following is a full, clear, and exact description thereof, reference being had to the accompanying drawings, and to the letters of reference marked thereon.

The nature of my invention consists in providing a circular door-spring with a forked vibrating piece of metal, and also providing the circular rod on which the spring works with a permanent plate at each end.

To enable others skilled in the art to make and use my invention, I will proceed to describe its construction.

Figure 1 is the door and frame.

Figure 2 is a circular spring on a bent rod, with a plate at each end.

Figure 3 is a piece operating on the spring.

Figure 4 is a coiled-wire spring.

A, in fig. 1, is the frame.

B, in fig. 1, is the door.

C C, in fig. 1, the hinges.

D, in fig. 1, a spiral spring.

E, in fig. 1, a bent rod of iron.

F F, in fig. 1, are plates.

G, in fig. 1, is a forked piece, attached to the door by the screw I.

The same letters of reference represent corresponding parts in the different figures, except H, which is a hole in the piece G in fig. 3.

Construction.

I make my spring of brass or steel wire, of suitable size to slip easily on a rod of iron five-sixteenths of an inch in diameter, and bent to a circle, or segment of a circle. For a gate, it requires to be about three-fourths of a circle. The plates F F are firmly secured to the ends of the rod E. The plates F F are then screwed on the door-frame. The spring D, encircling the rod E, is held to its place by the plates F F. The piece G is secured to the door by means of the screws I, which allow it to vibrate, so that it will work on an irregular circle.

Operation.

When the door is closed, the spring D presses against the vibrating piece I, and holds the door shut, and, as the door is opened, the vibrating piece I pushes back the spring D.

I do not claim applying a circular spring to a door and frame. Neither do I claim working the spring on a bent rod, as I am aware that they have all been used before.

I am aware of the patent to B. F. Whitaker; and What I claim as an improvement on his patent, is—

The stationary circular rod E, attached at both ends, with its supporter D, when used to contract the spring, in combination with spring D and plates F F, as constructed and shown, for the purpose set forth.

STEPHEN ELLIOTT.
